UNITED STATES PATENT OFFICE.

FRED K. LEWIS AND CHARLES R. ALLEN, OF ASHTABULA, OHIO, ASSIGNORS TO THE ASHTABULA BOW SOCKET COMPANY, OF ASHTABULA, OHIO, A CORPORATION OF OHIO.

TOP FOR VEHICLES AND THE LIKE.

Application filed November 2, 1921. Serial No. 512,274.

The object of the present invention is to provide an arrangement of bows and sockets with appropriate linkage whereby the top of an automobile or other vehicle may be wholly supported from a single main standard or bow that in the normal open position of the top will incline in a rearward direction so as to leave the sides of the car entirely clear. In such construction it is of course necessary that the operative parts be of substantial construction for the top is to be supported without sagging, and yet it is desirable that the various bows and connecting parts should fold up into a compact stack when the top is lowered.

To the accomplishment of the foregoing and related ends, said invention, then, consists of the means hereinafter fully described, and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a side elevation of a top-supporting structure or frame embodying our present improvements, such top being shown as mounted on an automobile body or tonneau of conventional form and as being viewed from the inside; Figs. 2, 3 and 4 are views similar to Fig. 1, but showing various modifications in the construction of our improved type; and Fig. 5 is a broken view similar to that of the preceding figures, showing still another modification in construction.

It is of course a matter of indifference whether the top is used on an automobile, motor boat, or otherwise, and, depending upon its longitudinal extent, a smaller or larger number of bows may be employed in the forwardly extending or outrigger structure of present interest, as indicated by the several modifications in this respect that are illustrated in the drawings. It will also be understood that the term "bow" is used here inclusively to designate, not merely the wooden bow proper, but also the metallic sockets or equivalent members that carry the same, these parts, when regarded in side elevation, constituting the equivalent of the so-called "sticks" in the all wooden bow type of construction. It is accordingly a matter of convenience to refer to the parts in the

singular, as though the structure lay in a single vertical plane, since the parts of interest do actually lie substantially in such a plane. As previously indicated, the top covering 1 is designed to be entirely supported through an outrigger structure from a single main bow or standard 2. The latter, which is of substantial construction in view of the weight it is thus designed to carry, is pivotally supported, or attached to, the body of the vehicle in the usual manner, so that it may be laid down and supported in a substantially horizontal plane when the top is not in use. Normally, in the extended or open condition of the top, said main bow 2 inclines rearwardly at an angle of approximately 45 degrees to the horizontal, being held from rising higher by the top covering, or by special straps (not shown), or extensions of the longitudinal strainers, which, as is well known, are used to connect the bows together and provide supporting means for the top covering intermediately between said bows. For the purpose in hand such straps or strainers do not require to be distinguished from, but may be regarded as a part of the covering material.

Referring first to the specific embodiment of my improved top illustrated in Fig. 1, the outrigger structure will be seen to comprise a main articulated auxiliary bow, or, as it is sometimes called, outrigger bow 6, the latter term referring more particularly to the outer portion or bow 7 proper, which is secured by means of an arm 8 (one on each side of course), pivotally attached to a supplemental bow 9 carried by the main bow 2. This supplemental bow may be directly pivotally attached to said main bow, as shown in Figs. 2, 3 and 4, or, as in the case of the specific construction shown in Fig. 1, said supplemental bow may be jointed, i. e., attached through the medium of a short link 9^a to said main bow. The joint between the two parts will in that event be a rule joint that locks in the extended position of the top. In order to sustain said bow 9 in such extended position of the top a link 10 connects the same at a point above the joint therein to a point on the main bow or standard 2 above the point of pivotal attachment of said bow 9 to the latter. Where a bow 9 is jointed as in the case of Fig. 1, link 10 may be a simple straight link, but where the bow 9 is continuous and directly pivoted on

the main bow, link 10 is replaced by two interconnecting links 10^a.

The point of attachment of swing arm 8 that forms the rear portion of outrigger bow 5 6 to supplemental bow 9 is preferably in line with, or just above the side edge of the top 10 covering 1, so as to be hidden by the latter, and such covering curves downwardly to the main bow 2 so as to similarly conceal the 15 lower end of said supplemental bow 9 and the links 10 or 10^a. The joint 11 between 20 said arm 8 and the outrigger bow 7 proper is a rule joint disposed so as to prevent forward bending of the arm in question when 25 extended in horizontal fashion, as in the open condition of the top illustrated in the several figures.

Where the top is of considerable horizontal 20 extent, as in the case of a two-seated vehicle, the covering 1 is desirably given support intermediate of the supplemental bow 9 and outrigger bow 7, by means of a second supplemental bow 12 that is pivotally attached to swing arm 8, as shown in 25 each of the several figures of the drawings. The operative connections between bows 9, 12 and 7 comprise a link 13 that connects said second supplemental bow 12 with outrigger bow 7 forwardly of the joint 11 and 30 another link 14 that connects bow 9 with said link 13.

The manner of operation of the two forms 35 of my improved top as illustrated in Figs. 1 and 2 should be readily understood. In other words, upon breaking the joint 11 downwardly the outrigger structure is caused to fold up, bringing bows 9, 12 and 7 into parallel relation, as shown in the dotted outline of the "stack" against main bow 2. In addition, in the construction of Fig. 1, 40 the joint in the supplemental bow 9, by bending downwardly, lowers the position of such outrigger structure with respect to said main bow so as to render said "stack" more 45 compact.

The difference between the constructions 50 shown in Figs. 1 and 2 has already been explained. In the case of Fig. 3 an articulated link 10^a is employed, just as in Fig. 2, to connect supplemental bow 9 with main bow 2. Instead, however, of a link 14 that 55 simply connects said supplemental bow 9 with the forward link 13 of the pair operatively interconnecting the two supplemental bows and outrigger bow 7, a link 15 is provided, the rear end 15^a of which projects beyond said bow 9 and is connected by another link 16 with articulated link 10^a, the 60 point of attachment of said link 16 with said last-mentioned link being preferably at the joint therein. The rearward extension 15^a of link 15 acts as a lever arm to break the joint in articulated link 10^a when the top 65 is being folded, and at the same time serves to lock said articulated link in its extended

position when the top is open. The manner in which the various bows and operating parts are disposed when the top is folded is clearly shown as before by the dotted outline of the "stack" formed by said parts 70 against main bow 2.

In the modified construction shown in Fig. 4 the forward member of articulated link 10^a is extended beyond supplemental bow 9 and the lever extension 10^b thus provided is connected by means of a link 17 with rearward extension 15^a of link 15. The link 17 just referred to will, in the open position of the top, lie disposed in substantially vertical position, and the rear end of swing arm 8 in this construction is pivotally attached to said link 17 instead of directly to supplemental bow 9. This permits of a shifting of the rear end of the spring arm, thus of the outrigger structure carried thereby relatively to said bow 9 when the top is collapsed, and thus assisting in the formation of a more compact "stack." At the same time the action of link 17 will correspond with that of link 16 in the previously described construction, both in the folding of the top and in more securely locking the parts in the open position of the top.

In the remaining construction, that shown in Fig. 5, the articulated outrigger bow 7 proper, instead of being directly pivotally attached to the forward end of swing arm 8, is connected therewith through the medium of a pair of links 20, 20 united by an upwardly bending rule joint 20^a, while the joints 11^a and 11^b, that unite the respective ends of said links 20 with the swing arm 8 and outrigger bow 7, bend downwardly just as joint rule 11 in the previously described constructions. The forward link 13 that is connected with supplemental bow 12 at its rear end is connected at its forward end with the rearmost of the two links 20, the disposition and connections of link 14 being the same as in Figs. 1 and 2. In addition, a link 21 is employed to connect said supplemental bow 12 with the outrigger bow 7 proper, being attached to the latter beyond the joint 11^b.

A further modification shown in Fig. 5 consists in the joining integrally of swing arm 8 with the forward part of the articulated link 10^a that connects the supplemental bow 9 with main bow 2. In other words, such forward member here becomes in effect a rearwardly extending section of the swing arm that acts directly as a lever in breaking the joint with the other member of link 10^a when the top is folded, and in holding such joint immovable in the open position of the top.

Other modes of applying the principle of our invention may be employed instead of the one explained, change being made as 130

regards the mechanism herein disclosed, provided the means stated by any of the following claims or the equivalent of such stated means be employed.

5 We therefore particularly point out and distinctly claim as our invention:—

10 1. In a top for vehicles and the like, the combination of a main support attached to the top of the vehicle, a supplemental bow pivotally attached to said support, an articulated auxiliary bow pivotally attached to said supplemental bow, a second supplemental bow pivotally attached to the rear portion of said auxiliary bow, plural interconnected links connecting the outer portion of said auxiliary bow and said two supplemental bows, plural interconnected links connecting said first-named supplemental bow with said support and adapted to sustain the same in inclined position relatively to said support when the top is open, and means operatively connecting said two sets of interconnected links.

25 2. In a top for vehicles and the like, the combination of a main support attached to the top of the vehicle, a supplemental bow pivotally attached to said support, an articulated auxiliary bow pivotally attached to said supplemental bow, a second supplemental bow pivotally attached to the rear portion of said auxiliary bow, plural interconnected links connecting the outer portion of said auxiliary bow and said two supplemental bows, plural interconnected links connecting said first-named supplemental bow with said support and adapted to sustain the same in inclined position relatively to support when the top is open, and link and lever means operatively connecting said two sets of interconnected links.

30 3. In a top for vehicles and the like, the combination of a main support attached to the body of the vehicle, a supplemental bow pivotally attached to said support, an articulated auxiliary bow pivotally attached to said supplemental bow, a second supplemental bow pivotally attached to the rear portion of said auxiliary bow, plural interconnected links connecting the outer portion of

50 said auxiliary bow and said two supplemental bows, the rear-most of said links having a lever extension, plural interconnected links connecting said first-named supplemental bow with said support and adapted to sustain the same in inclined position relatively to said support when the top is open, and a link connecting the lever-extension of said first set of interconnected links with said last set of such links.

55 4. In a top for vehicles and the like, the combination of a main support attached to the body of the vehicle, a supplemental bow pivotally attached to said support, an articulated auxiliary bow pivotally attached to said supplemental bow, a second supplemental bow pivotally attached to the rear portion of said auxiliary bow, plural interconnected links connecting the outer portion of said auxiliary bow and said two supplemental bows, the rear-most of said links having a lever extension, plural interconnected links connecting said first-named supplemental bow with said support and adapted to sustain the same in inclined position relatively to said support when the top is open, and a link connecting the lever-extension of said first set of interconnected links with the point of interconnection between said last set of such links.

60 5. In a vehicle top, the combination of a single rearwardly inclining main bow pivotally supported on the vehicle body, a supplemental bow carried by said main bow, the connection between such supplemental and main bows including plural links whereby said supplemental bow may be supported in a forwardly inclined position or be folded up alongside said main bow, a foldable outrigger structure carried by said supplemental bow, and separate means pivotally connected to said outrigger structure for causing the aforesaid links to fold up said supplemental bow when said outrigger structure is folded.

65 Signed by us, this 31st day of October, 1921.

FRED K. LEWIS.
CHARLES R. ALLEN.
